(57) **CLAIM**

The ornamental design for the pre-cut body tape for the wrist, as shown and described.

DESCRIPTION

FIG. 1 is a perspective view of a pre-cut body tape for the wrist;

FIG. 2 is a top view of a pre-cut body tape for the wrist;

FIG. 3 is a bottom view of a pre-cut body tape for the wrist; and,

FIG. 4 is a left side view of a pre-cut body tape for the wrist with the right side view being a mirror image of the left side view.

The broken lines showing a human hand and arm illustrates environmental structure and forms no part of the claimed design.
